METHOD OF ABSORBING AND CONDENSING
DIGESTION GASES AND VAPORS

Albert D. Merrill and Thomas L. Dunbar, Watertown, N. Y., assignors to Chemipulp Process Inc., Watertown, N. Y., a corporation of New York

Application June 26, 1935, Serial No. 28,580

17 Claims. (Cl. 92—7)

This invention relates to improvements in the digestion of fibrous material, and more particularly to an improved method of and apparatus for absorbing and condensing gases and vapors evolved during the digestion treatment.

It has been proposed heretofore to utilize a flowing stream of acid to withdraw and condense gases generated or evolved in a pulp digester as well as from other units of a digestion system. A typical example of such use is the employment of an eductor for withdrawing gases and vapors from the vapor space of a digester. In such prior use relatively cold acid was pumped, at relatively high velocity, through the nozzle of an eductor and this stream utilized to induce a flow of gas from the digester. Such eductors usually comprised a single gas inlet and a single nozzle with a valve means associated with the nozzle to control the flow of liquor therethrough.

To date but little attention has been paid to the proper design of such eductors. These units, however, are very important in respect of the efficient operation of a pulp digestion system since they perform a number of important functions. They serve in the first instance as a pressure control means to adjust and/or maintain a desirable low pressure in the digester because of the fact that this pressure is due substantially completely to condensable gases (SO_2) and vapors (H_2O). The quantity or degree of such condensation therefore largely controls the pressure in the digester. Secondly such eductors serve as a combined heat exchanger and mixer inasmuch as they provide a zone in which cold acid is caused to condense and absorb hotter gases and vapors, thus uniformly increasing the temperature and concentration of the acid.

As a result of considerable experimentation we have found that if an eductor is properly designed its efficiency can be very greatly increased. The novel construction and operation of the improved eductor, to be described, is based upon a recognition of factors, obtaining in this art, which heretofore were either unappreciated or were disregarded.

An object of the invention therefore is to provide an improved method of controlling pressure in a pulp digester.

Another object is to provide a novel method of withdrawing and condensing condensable gases and vapors evolved in a pulp unit.

A further object is to condense condensable gases and vapors in a pulp digestion unit by utilizing a plurality of streams of absorbing fluid.

Another object is to provide an eductor of im-

proved design by reason of which optimum induced flow of gases and vapors is secured.

Yet another object is to provide a novel method of controlling the quantity of gas flowing through an eductor.

A still further object is to devise means for insuring optimum stream line flow of gases through an eductor.

An additional object is to devise an eductor in which a plurality of zones are provided for the direct contact of liquid and gases and/or vapors.

With these and other equally important and related objects in view the invention comprehends the concept of providing an eductor of special design in which the size of the liquor inlet pipe is specially correlated with respect to the position of the gas inlet so as to achieve improved results and in which improved adjustable control and optimum absorption are secured by utilizing a split or plural stream of the absorbing liquid. By reason of the provision for adjustable control the eductor may be substantially standardized so as to fulfill the requirements of plant units of varying capacity.

In order to enable a more ready comprehension of the underlying principles of the invention preferred illustrative embodiments are shown in the accompanying drawings, in which—

Figure 1 is a diagrammatic illustration of a hot acid unit embodying the improved operation and structure.

Fig. 2 is an enlarged longitudinal section of one modification of the improved eductor.

Fig. 3 is a cross section taken on line 3—3 of Fig. 2.

Fig. 4 is a central longitudinal section of another type of eductor.

Fig. 5 is a detail of the eductor shown in Fig. 4.

Fig. 6 is a diagrammatic illustration of the type of flow of the fluids through the eductor.

As shown in the drawings and as is now known in the art, the major elements of the apparatus include the acid storage tank 1, hot acid accumulator 2 and one or more digesters 3. Cold acid may be pumped from the acid storage tank by means of pump 4 and forced through line 5 and check valve 5' to the eductor 10, through main eductor branch 6, controlled by valve 6' and optionally through branch 7 controlled by valve 7' in a manner more particularly to be described. Cold acid from branch 6 passes at relatively high velocity through nozzle 8 and induces a flow of gas and/or vapor through the relief header 9. The cold acid condenses and absorbs the hot relief gases and vapors and is correspondingly

and proportionately preheated. The combined fluid stream then passes downwardly through drop leg 11 to second eductor 12. Here the fluids are contacted with a stream of acid recycled to 5 and from the accumulator whereby further condensation and absorption is insured and the pressure in line 11 correspondingly reduced. Such cooling and absorbing stream is withdrawn from the accumulator through line 13, pump 14 and 10 nozzle 15, thence through valve 16 back to the accumulator. The flow of liquid through the recycle line may be controlled by proper adjustment of valve 15'. As will be appreciated, since eductors 10 and 12 are in series, maximum condensation and absorption, and hence maximum 15 reduction in pressure in header 9, is secured, while at the same time the make-up acid entering through line 5 is preheated.

In the operation of this type of plant, as is 20 now known to those skilled in the art, the digester is first filled with chips by removing the manhole cover 20 and feeding the chips in by gravity or by means of a chip packing device. After the digester has been filled with chips the valve 21' 25 in the top relief line 21 is opened, valve 22' in side relief line 22 and valve 23' in high pressure header 9 are closed. Valve 24' in the low pressure relief branch 26 is closed and air vent valve 25' is opened. Hot acid is then withdrawn 30 from the accumulator 2 through the line 30 and forced by the digester filling pump 31 through header 32 into the branch line 33. As the hot acid enters the digester the air contained therein is correspondingly displaced and is discharged 35 through the open valves 21' and 25' to the atmosphere. Valves 21' and 25' may be kept open until the digester is completely filled with liquor or until gas appears at the vent valve 25'. When such gas appears valve 25' may be closed and 40 valve 24' opened, valve 21' remaining open so as to pass such gas through the relief header 26 and thence through drop leg 27 to the acid storage tank. When the digester is completely filled valves 24' and 21' are closed.

45 Thereupon, that is to say when the digester is charged with chips and is filled or substantially filled with liquor, operation of the pump 31 may be continued so as to force in additional hot acid and build up any desired hydrostatic pressure within the digester. In the usual run pump 31 is continued in operation until pressure of the order of from fifty to ninety pounds per square inch is developed in the digester. Thereafter flow of acid from the 50 accumulator to the digester may be discontinued either by stopping the pump or closing a valve in the branch 33.

Then, if desired, in order to insure a thorough 60 penetration of the chips with the hot acid and to equalize the temperature throughout the digester, the digester recirculation circuit may be operated. This may be done, as will be noted, by opening valve 40', operating pump 41, and thus withdrawing acid from the upper portion 65 of the digester through line 40 and discharging it into the lower portion of the digester through line 42. This recycling is maintained until the desired conditions obtain, such conditions being a thorough penetration or saturation of the chips 70 with acid at a substantially uniform and equalized temperature throughout the digester. Such precirculation-soaking period may be maintained for a period of from one-half to two hours.

At the end of the soaking period the chips 75 within the digester are uniformly penetrated with

hot acid at a temperature of from 75° C. more or less to about 100° C. Then, as more particularly explained in copending application of Thomas L. Dunbar, Serial No. 758,314, the liquid level within the digester is lowered by drawing off 5 relief liquor through side relief line 22 and passing it by way of relief header 9, eductor 10 and drop leg 11 to the accumulator. Upon the lowering of the liquid level in the digester there is an abrupt drop in pressure from the existing 10 pressure of 50 to 90 lbs. down to 30 lbs. more or less. This drop in pressure, as will be understood, permits the use of low pressure steam for bringing the mass up to cooking temperatures. Upon lowering of the liquid level to the 15 desired extent steam is then admitted to the digester through steam lines (not shown) connected to the bottom cone of the digester.

This admission of steam soon builds up the 20 pressure within the digester and the temperature correspondingly increases at a rapid rate. When the pressure has been raised to the desired operating level it may be maintained at this value by opening valves 21' and 23'. During the cooking operation the liquid level rises due to the 25 condensation of steam. Some time after the initiation of the cook the top relief valve 21' may be closed and the side relief line 22 opened so as to maintain the proper liquid level. Thus in normal operation the side relief line may be 30 opened at about the fourth or sixth hour of the cook. In the manner well known to those skilled in the art, by the proper manipulation of the valves 21' and 22' the desired pressure and liquid 35 level may be maintained.

If desired, during the actual cooking or digestion process liquor may be recycled to and from the digester by operating the digester recycle line 40'-40-41-42.

As explained more fully in the copending application referred to, steam is shut off some time prior to the completion of the cook and the pressure is gradually reduced down to about 20 to 30 lbs., after which the material is then discharged into the blow-pit or is first washed with 40 water and then discharged.

As is known, during the complete treatment 45 of a mass of chips, high pressure gases and relief liquids may be passed through the line 9 and thence through the eductors 10 and 12 to 50 the accumulator. Low pressure gases may be passed through line 26 and eductor fitting 28 through the drop leg 27 into the acid storage tank. The eductor 28 may, if desired, be of substantially the same type as eductor 10 or any 55 other preferred design.

As explained in copending application Serial No. 758,314, the pressure conditions obtaining in the system, and particularly in the accumulator, may be accurately controlled within a relatively narrow range. This may be achieved by means of the vent line 50 connected at one end through the valve 50' to the vapor space of the accumulator and at the other through a fitting 51 to the drop leg 27. The valve 50' is preferably a pressure regulating valve adjusted to a predetermined setting so that when the pressure in the accumulator exceeds this point gases are automatically vented through the line 50 to the storage tank. In normal operations the valve 50' may be set so as to vent such gases at pressures of from 25 to 100 lbs. more or less. Similarly a by-pass line 54 is connected at one end to the high pressure relief line of the digester and at the other end through the valve 54' to the

5 accumulator. The valve 54', like valve 50', is a pressure regulating valve. This may be set at any desired pressure differential of from the order of 1 to 4 or more pounds. In these circumstances 5 when the pressure in the relief line 9 exceeds by this amount the pressure in the accumulator, the valve 54' automatically operates and fluids are by-passed around eductor 10 and introduced directly into the accumulator.

10 The digester and accumulator are provided, as is known by those skilled in the art, with pressure, temperature and liquid level indicating and/or recording devices.

15 This type of operation is greatly improved by utilizing the novel eductor. As shown in Figs. 1 and 2 the stream of cold acid forced through line 5 may be split into streams, one passing through line 6 and the other passing through line 7. The acid entering through line 6 passes downwardly 20 through the central pipe or channel 60 and is ejected through the nozzle 8. Acid flowing from line 7 enters the eductor at a point approximately opposite the entrance of the relief fluids, that is to say in the area of the outlet of header 9.

25 In the preferred operation acid is forced through lines 5 and 6 so that a relatively high pressure obtains at the nozzle 8. Operations have been conducted in which the pressure at this point is about 110 lbs. per sq. in. gauge. The size 30 of the pipe 60 and the nozzle 8 is specially designed so that for normal operation of the plant the control valve 6' is completely opened. The nozzle thus discharges the required amount of liquor without utilizing the auxiliary stream passing through line 7. If for any reason the plant capacity is increased over the normal capacity, the additional liquor requirements are satisfied by opening valve 1' and passing the additional stream into the eductor. In these circumstances 35 the cold acid flowing through line 7 immediately contacts the gases entering from header 9 and effects a condensation and reduction of pressure at this zone. The liquor flowing through the nozzle 8 at relatively high velocity establishes a 40 zone of correspondingly reduced pressure which acts to induce a flow of fluids downwardly through the eductor.

45 In the preferred type of operation an auxiliary condensing stream for the low pressure gases is also provided. As shown, a line 70, controlled by valve 70', is connected to the cold acid line 5. Such line communicates with the upper end of the drop leg 27 through a suitable eductor type of fitting 28. Cold acid flowing through the line 55 70 thus contacts with low pressure gases flowing in through header 26 and cools, condenses and absorbs such gases. This condensation and absorption reduces the pressure in line 26, causing a rapid flow of fluids therethrough.

60 The cold acid pump 4 is so designed that it will maintain a pressure at the nozzle 8 of the order of 110 lbs. and will deliver 50% more liquor at that pressure than is actually required for a given operation.

65 As shown in Fig. 4, more rapid contact and consequent condensation of gases may be obtained by feeding the relief fluids into the eductor in a plurality of streams. Thus the tubular eductor casing 10 is provided with two elbows 61 70 and 62. These are connected to two branches leading from header 9. Preferably the inlets 61 and 62 are diametrically positioned and are in the same zone as the liquid inlet 63, which latter is connected to the auxiliary cooling acid line 75 70. As in the eductor shown in Fig. 2, the main con-

densing stream of acid enters the eductor through the central tube 60 and extends downwardly, below the gas inlet 61—62, a predetermined distance, as will be more fully explained. In the operation of this type of eductor streams of gases entering the inlet 61—62 respectively mutually impinge in the central area of the eductor and at that point, of high turbulence, may be contacted with a cooling stream of acid admitted through branch line 7. The acid flowing downwardly 10 through nozzle 8 establishes a reduced pressure at this zone, which pressure sucks or aspirates fluids from the upper section of the eductor. In the area about nozzle 8, therefore, the relief fluids are intimately contacted with cold acid flowing 15 at relatively high velocity.

20 In this type of eductor, therefore, there is provided two condensing and/or absorbing zones. The first or main zone in the area about nozzle 8 operates continuously and fulfills the normal requirements of a given installation. A supplemental condensing zone is provided, as explained, in the upper portion of the eductor and comes into play when cold acid is admitted through the separate line 7.

25 The specific mechanical construction of the eductor may of course be widely varied. To facilitate assemblage and servicing, that in the drawings is preferred. Thus a complete unit may comprise a fitting 80 and the tube 60. This fitting 30 may be a casting of a suitable corrosion resistant metal or alloy and is provided with the terminal flanges 81 and 82. Such fitting is formed with the gas inlet (or inlets) 83 which is provided with the peripheral flange 84. The flanges are tapped 35 in the usual manner to provide for attachment to a corresponding coupling flange on the header 9. The eductor fitting is also formed with the liquor inlet pipe section 85, which is suitably formed to provide for tight attachment to the acid line 7. 40

45 The tube 60 preferably constitutes a separate member. This is formed at its upper end with an integral lateral flange, of greater diameter than the bore of fitting 80, so as to seat upon the upper flange 81. The tube is provided at suitable points with spacer lugs 90 (see Fig. 3). Such lugs are preferably of stream line form in cross section so as to diminish resistance to flow.

50 The upper end of the drop leg 11 may be formed with a flange 11' which is tightly held between the bottom flange 82 of the fitting and the coupling ring 91. It will be understood of course that interposed between the respectively cooperating flanges or abutting surfaces are suitably corrosion resistant packings or glands. 55

55 It is particularly to be observed that in a preferred structure the liquid inlet 85 extends at an angle to the central axis of the tube and to the axis of the header 9. In other words, liquor entering through the line 7 and pipe section 85 60 impinges the entering stream of gas tangentially, thus deflecting the flow of gas downwardly and centrally of the fitting and drop leg.

65 As a result of considerable experimentation we have found that in order to secure the best results in this type of operation, that is to say in the utilization of an eductor, the length of the pipe 60, or its equivalent, is very important and substantially critical. Specifically we have found that in order to obtain optimum results the length 70 of the tube 60, below the gas inlet, should be about 4 ft. (see Fig. 6). We have further found, paradoxically, that variations in the diameter of the pipe 11 do not substantially affect this factor. In other words, we have found as a mat- 75

ter of actual experimentation that this distance of 4 ft. should be insured whether the diameter of the pipe is 4, 12 or 16 inches. It would seem that, given a certain pump pressure, the fact 5 that the velocity of the efflux stream from the nozzle 8 will vary with the diameter of this nozzle and as a corollary the pressure in the zone of the nozzle will correspondingly inversely vary, that the requisite length of the pipe section 10 would be commensurately affected. It is probable that within a certain degree this is true but, as noted above, we have found that for usual diameters of the nozzle 8, the best results can only be achieved by having the pipe section 60 of a 15 length of the order of 4 ft. below the gas inlet. A typical eductor which has successfully been employed comprises one having an 8 inch bore, a central liquor pipe (60) of 3 inch diameter, and 1 1/2 inch nozzle, and a gas inlet of 8 inch diameter. 20 While attempting no accurate rationale of this result, it would appear that the peculiar effectiveness of this particular length is due to stream line flow, as diagrammatically illustrated in Fig. 6. During operation gas enters the eductor fitting from the line 9 at a pressure of the order 25 of 70 lbs. or less. As pointed out above, the fluid pressure of the entering liquid, at the nozzle 8, is of the order of 110 lbs. per sq. in. The gas entering the eductor fitting is deflected substantially at 30 right angles and, due to its elasticity, is in a turbulent or burbling condition for a considerable period of time, despite the rapid flow of liquor from the discharge nozzle 8. It would appear then that the effectiveness of this particular 35 pipe length is due to the fact that it insures an extended length of travel, in which length the gases and/or vapors are extenuated from a turbulent, swirling or burbling condition to one of stream line or filament flow. In other words we 40 believe the situation here is analogous to that obtaining to aerodynamics where, to insure the maximum lift, that is to say the greatest continuity of airflow, the airfoil must be maintained below what is known in that art as the critical or 45 bubble angle. At any rate we find as a matter of actual fact that if the conditions outlined above are fulfilled, improved operations are secured.

We have found that in this art there is a special 50 relationship existing between the character and/or condition of the condensable medium and the length of its travel under induced flow. We have found further that in a typical pulp plant optimum results in respect of pressure control 55 and condensation may be achieved by utilizing a relatively long length of pipe section 60, or, stated differently, by displacing the liquid efflux some considerable distance from the gas inlet, such distance being sufficient to insure extenuation 60 of the relatively elastic gaseous or vaporous medium from a swirling or turbulent motion into a substantially stream line flow. In these circumstances liquid discharges from nozzle 8 into a substantially parallel encasing stream of gases 65 and vapors, thus insuring optimum induction effect, condensation and absorption.

The novel eductor has been described particularly with respect to its utilization in the high pressure relief line. It will be manifest, however, 70 that this improved structure may be employed at any other point in the pulp plant or in any other art or circumstances where the same results are desired and comparable conditions obtain.

While a preferred structure has been described, 75 it is to be understood that this is given for the

purpose of explaining the principle of operation of the device. The invention is considered to reside in the several broad concepts defined, such as the utilization of a plurality of streams of condensing medium and the principle of optimum displacement of the nozzle from the gas inlet. 5

We claim:

1. In a cellulosic pulp digesting process that method of recovering the chemical and thermal values of evolved gases which comprises admitting 10 such gases to an eductor and contacting the gas therein with a plurality of streams of condensing liquid and utilizing the resultant liquid for digesting cellulosic material.

2. In a cellulosic pulp digestion process that 15 method of recovering the chemical and thermal values of evolved gases and vapors, which comprises admitting such gases to an eductor zone and contacting the gas therein with a plurality of streams of cellulosic pulp digestion liquor at different 20 sections of the zone.

3. That method of inducing a flow of gas from a digestion zone of a cellulosic pulp digestion process in which gas is evolved which comprises admitting such gas to an eductor, contacting such 25 gas immediately with a stream of a relatively cool cellulosic pulp digestion liquor, passing the combined stream through a predetermined travel and then contacting such combined stream with a separate stream of cellulosic pulp digestion 30 liquor.

4. That method of inducing a flow of gas from a pulp digester of a cellulosic pulp digesting process which comprises connecting the vapor space of the digester through a conduit to an eductor, 35 admitting a stream of relatively cool cellulosic pulp digestion liquor to the eductor adjacent the area of admission of the gas, and admitting another stream of such digestion liquor to the eductor at a point displaced from the inlet of the gas. 40

5. In a cellulosic pulp digestion process that method of recovering the chemical and thermal values of evolved gases and vapors which comprises admitting such gases to an eductor zone and contacting the gas therein with a plurality of 45 differential velocity streams of digestion liquor, and utilizing the resulting liquor for the digestion of cellulosic material.

6. A method of recovering the chemical and thermal values of gases evolved in a cellulosic 50 pulp digestion process which comprises admitting such gases to an eductor in a plurality of streams and contacting the gas in the eductor with a plurality of streams of relatively cool digestion liquor, and utilizing the resulting liquor for digestion 55 of cellulosic material.

7. A method of reducing the pressure in a pulp digester and recovering the chemical and thermal units of evolved gases and vapors which comprises connecting the vapor space of the digester 60 through a conduit to an eductor, admitting a stream of cooling and absorbing liquid to the eductor adjacent the inlet of the gases and vapors and in a direction tangential to the entering stream of gas, admitting a second stream of cooling liquid to the eductor at a point displaced from the gas inlet and in a direction substantially parallel to the flow of gas at such point.

8. A method of withdrawing gases from a cellulosic pulping operating plant unit in which such 70 gases are evolved which comprises admitting a stream of the gas to an eductor, partially condensing such gases adjacent the point of admission to the eductor, forcing a stream of relatively cool cellulosic pulp digestion liquor into the educt- 75

tor at a point sufficiently displaced from the gas inlet that at such point the gases have assumed a non-turbulent, substantially stream line flow, and then utilizing the resulting liquor for the digestion of cellulosic material.

9. A pulp digestion process comprising cooking a mass of fibrous material in a digester with acid liquor, withdrawing gases and vapors from the vapor space of the digester and passing such gases and vapors to an eductor, contacting the gases in the eductor with plural streams of relatively cool acid liquor and discharging fluids from the eductor to an accumulator.

10. A method of reducing the pressure in a pulp digester in which cellulosic material is pulped, and recuperating the thermal and chemical values of evolved gases which comprises, admitting gases evolved in the digester to an eductor in a plurality of streams and contacting such gas in the eductor with a stream of relatively cool cellulosic digestion liquor, and utilizing the resulting liquor for digestion of cellulosic material.

11. A method of reducing the pressure in a pulp digester in which cellulosic material is pulped, and recuperating the thermal and chemical values of evolved gases which comprises, admitting gases evolved in the digester to an eductor in a plurality of mutually impinging streams and contacting the combined stream of gas in the eductor with a stream of relatively cool cellulosic digestion liquor, and utilizing the resulting liquor for digestion of cellulosic material.

12. In a cellulosic pulp digesting process that method of recovering chemical and thermal values of evolved gases which comprises, admitting such gases in a plurality of streams to an eductor and contacting the gas in the eductor with a plurality of differential velocity streams of relatively cool cellulosic digestion liquor, and utilizing the resulting liquor for digestion of cellulosic material.

13. In a cellulosic pulp digesting process that method of recovering the chemical and thermal values of evolved gases which comprises admitting such gases in a plurality of mutually impinging streams to an eductor, admitting a stream of relatively cool cellulosic digestion liquor to the eductor in the zone of impingement and admitting a second stream of similar relatively cool digestion liquor at a point displaced from said zone.

of impingement and utilizing the resulting liquor for the digestion of cellulosic material in the process.

14. A method of digesting pulp which comprises cooking a mass of fibrous material with acid liquor in a digester, withdrawing gases and vapors evolved in the digester and passing them through a conduit to an eductor; forcing a stream of relatively cool acid liquor from a container toward the eductor, splitting such stream of cooler acid and optionally admitting the split streams to the eductor at a plurality of points therein; passing low pressure gases from the digester through a second conduit and contacting such gases with a split stream of acid derived from the said first acid stream.

15. A pulp digestion process comprising cooking a mass of fibrous material in a digester with a digesting liquor comprised of a volatile component, withdrawing volatile components from the vapor space of the digester and passing such volatiles to an eductor, contacting the volatiles in the eductor with plural streams of relatively cool digestion liquor and discharging fluids from the eductor to an accumulator.

16. In a cellulosic pulp digesting process, that method of recovering the chemical and thermal values of evolved gases which comprises admitting such gases in a plurality of mutually impinging streams to an eductor, preliminarily condensing the gases adjacent the point of admission by contacting said gases with a stream of relatively cool cellulosic digestion liquor and further condensing said gas by admitting a stream of relatively cool cellulosic digestion liquor to the eductor at a point displaced from said zone of impingement and utilizing the resulting liquor after such contact as a cellulosic digestion reagent.

17. In a cellulosic pulp digesting process, that method of recovering the chemical and thermal values of evolved gases which comprises admitting such gases to an eductor and connected drop leg, and contacting and condensing the gases therein with a plurality of streams of relatively cool cellulosic digestion liquor, said plural streams respectively contacting the gases at different points along the line of flow of the gases in the eductor and then utilizing the condensing liquid as a digestion reagent in the pulping process.
